UNITED STATES PATENT OFFICE.

THOMAS MILLER, OF BROOKSVILLE, KENTUCKY.

TOBACCO PRESS.

Application filed April 11, 1927. Serial No. 182,591.

My invention relates to certain new and useful improvements in tobacco presses, and has for one object to provide a simple, cheap, yet efficient and durable press in which tobacco may be quickly and easily compressed in packages and the compressed bundle readily removed.

Another object is to provide a means for readily adjusting the presser board to suit different heights of packages or bales, and also to provide a means whereby the presser board may be quickly and readily released from the package for the removal thereof.

Another object is to provide a presser board which shall be a permanent part of the press, yet easily placed in position out of the way of the reloading of the press.

Another object is to provide such a press adapted to be positioned in a novel manner upon the wall of the baling shed whereby to greatly facilitate the loading of the press and the removal therefrom of the package after being baled.

Another object is to provide a means whereby the presser board may be readily adapted to maintain a parallel relation with the back of the press, thereby facilitating the pressing operation.

Another object is to provide a means whereby the presser board may be freely released after the pressing operation, as by the simple operation of a lever.

Another object is to provide a means whereby the sticks of tobacco to be pressed may be readily inserted into the press and readily removed therefrom.

Another object is to provide a means whereby the bottom gate of the press may be readily and easily adjusted to suit the height of the package so as to prevent the drying out of the tobacco.

With the above and other objects in view, my invention consists in the combination and arrangement of parts hereinafter described and claimed, and more fully illustrated in the preferred embodiment shown in the accompanying drawings, wherein

Figure 1 is a side elevation of my device with the presser board raised.

Figure 2 is a bottom view of Figure 1.

Figure 3 is a side elevation of my device with the presser board lowered and pressing a package of tobacco, parts of the device being shown in section.

Figure 4 is a detail in top plan of the presser board latch.

Referring now more particularly to the drawings, I provide a press composed of side boards 5, 6, positioned in spaced and parallel relation as by the bottom board 7, and cross piece 8. The back face 9 of the side boards 5 and 6 is formed at an angle to the front face 10 thereof; the back board 11 is positioned in parallel relation to the said front face 10; by the arrangement described the device is adapted to be mounted on the wall of the bale shed (not shown) so that any tobacco placed in the press will have a tendency to lay against the back board. The said back board 11 is positioned in spaced and parallel relation to the bottom board 7 and front face 10 of the side boards 5, 6, and extends from side board to side board. A flexible apron 12 is slidably positioned between the said bottom board 7 and the back board 11, as by guide slots 13 provided in the side boards 5, 6, the said guide slots 13 also extending out from under the said back board 11 and thence right angularly extending to the front face 10 of the side boards. The side boards 5, 6 each have a feed slot 14 at the upper end of the board, the said feed slot being formed with diverging walls, of which the lower wall, as at 15, is formed at right angles to the front face 10 of the board, and serves as a rest for the sticks 16 of the tobacco bundles 17, as shown in Figure 3. The presser board slots 18 are formed in corresponding relation to each other in the side boards 5, 6, above the feed slots and extending right angularly of the front face 10 aforesaid, from a point oppositely the said back board 11 to a point near the front face 10 of the side boards.

The presser board 19 is provided with spaced and parallel handles 20 extending beyond both ends of the presser board. One end of each of the handles 20 is formed into a latch or pawl 22 and is mounted on a rod 21 adapted to slidably engage the said presser board slot 18 in the side boards 5, 6. The other end of the handle 20 is formed with a hand grip 23, and between the hand grip and the presser board the handle is formed into a longitudinally extending triangular pawl 24. The presser board is adapted to fit in between the side boards 5, 6, as shown in Figure 2.

A latch bar 25 having a plurality of notches 26 is pivoted in a plane parallel to and on the inside of each of the side boards 5, 6, at the upper ends and near the back

thereof, and is so shaped as to be co-extensive with the presser board slot 18. The said latch bars by reason of their weight, are adapted to be urged against the pawls 22 of the handles 20 which are constructed so as to be positioned oppositely the latch bars, whereby the said notches are adapted to engage the said pawls. An arm 27 is provided on the back side of each of the latch bars 25; flexible elements or chains 28 each have one end pivoted to one of the arms 27, and the other end pivoted to cranks 29 mounted on the transverse shaft 30 journaled in the side boards 5, 6. One end of the said shaft 30 extends through and outwardly the side board 5 and has a crank 31 mounted thereon and pivoted to an articulated handle 32 pivoted to the side board 5 as at 33. One end of the handle 32 is provided with a hand grip 34; the other end is articulated as by a pin 35 and angularly disposed and coacting faces 36, whereby one part of the handle is adapted to act as a crank, and the other as a link, such that rotation of the handle 32 about the pivot point 33 will rotate the shaft 30 as by the crank 31.

A latch bar 39 having a plurality of notches 40 is pivoted in transverse relation to and on the bottom face 41 of each of the side boards 5, 6, and near the back portion thereof and adapted to extend substantially the depth of the press. A portion of the bottom board 7 is extended downwardly as at 37 so as to form guides 38 for the latch bars 39. Normally the said latch bars 39 are adapted to be positioned so as to have the said notches 40 engage the said pawls 24 as by a spring 42 mounted on each end of the cross piece 8 and bearing against the outside of each of the latch bars 39. An arm 43 on the end of each of the latch bars 39 is pivoted to a slotted link 44 slidably pivoted to an equalizing bar 45 pivoted as by a link 46 to a crank 47 mounted medially the shaft 30.

In use, the device being in the position shown in Figure 3, the articulated handle 32 is thrown into the position shown in Figure 1, whereby the shaft 30 is rotated so as to cause the cranks 29 to pull on the chains 28 whereby the latch bar 26 is lifted against its weight out of engagement with the pawls 22, as shown in Figure 1. At the same time, the crank 47 pulls on the equalizing bar 45 as by link 46, thereby causing the slotted links 44 to rotate the latch bars 39 about their pivot points against the springs 42 so as to disengage the said latch bars from the pawls 24, as clearly shown in Figure 2. The presser board 19 may now be swung upwardly about the rod 21 and slid backwardly guided by the slot 18 so as to be substantially out of the way, as shown in Figure 1. The presser board is locked in this position as by a latch shown in Fig-

ure 4, and comprising two spring set and coacting pawls 48 and 49, mounted on the front face 10 of one of the side boards, as the side board 5, and oppositely the slot 18 aforesaid. The action of the latch is as follows:

When the presser board is swung up one of the handles 20 will engage the pawl 48, rotating it against the action of the spring 50, so that the handle 20 and the presser board 19 may slip past the pointed nose 51 of the pawl 48, whereupon the handle 20 will furthermore engage the spring set pawl 49 as by the flat nose 52 thereof, which acts as by a frictional engagement of the pawl 49 with the handle 20 so as to assist the pawl 48 to hold the presser board 19 up, against its weight, out of the way of the operator, who is now able to remove the pressed package as at 17 from the press. If desired, the flexible gate 12 may then be pushed under the back board 11, and the device will then appear as in Figure 1, and Figure 2.

The operator then takes fresh bundles of tobacco, and slides the sticks 16 thereof into the slot 14, letting the sticks rest on the face 15 of the slot. He then moves the articulated handle to the position shown in Figure 3, thereupon releasing the latch bars 25 so that they are free to fall of their own weight against the pawls 22 of the handles 20 when the presser board 19 is moved by the operator into the position indicated generally in Figure 3 and adapted to press the tobacco as by the operator grasping the hand grips 23. At the same time, the latch bars 39 are also released so that they are urged as by the springs 42 to engage the pawls 24 of the handles 20 as the operator brings the presser board into engagement with the tobacco, as described. As the tobacco is being pressed, the operator draws the flexible gate 12 out from under the back board 11 so as to close up the space between the back board and the presser board, and as the pressing proceeds, the presser board is caused to move progressively towards the back board as by the pawls 22 and 24 successively engaging the latch bars 25 and 39, respectively, the flexible gate always adapting itself to the diminished size of the opening between the back board and the presser board, whereby the tobacco is prevented from drying out.

I claim:

1. A press of the character described, comprising a fixed back board, side boards mounted on the back board, said side boards having transversely extending corresponding slots at one end thereof, a transverse bar slidably engaging said slots, a presser board mounted on said bar, said presser board being adapted to co-operatively engage said side boards and said back board, and means for adjustably positioning said presser board

- with relation to said back board, for the purposes described.
2. A press of the character described, comprising a fixed back board, side boards mounted on the back board, said side boards having transversely extending corresponding slots at one end thereof, a transverse bar slidably engaging said slots, a presser board mounted on said bar, said presser board being adapted to co-operatively engage said side boards and said back board, latch bars pivoted to said side boards and operatively engaging said presser board, a transverse shaft journaled in said side boards, a crank on each end of said shaft, flexible elements each having one end pivoted to one of the latch bars, and the other end pivoted to one of said cranks, and means for rotating said shaft.
3. A press of the character described, comprising a fixed back board, side boards mounted on the back board, said side boards having transversely extending corresponding slots at one end thereof, a transverse bar slidably engaging said slots, a presser board mounted on said bar, said presser board being adapted to co-operatively engage said side boards and said back board, upper and lower latch bars pivoted to said side boards an operatively engaging said presser board, a transverse shaft journaled in said side boards, end cranks mounted at each end of said shaft, flexible elements each having one end pivoted to one of the upper latch bars, and the other end pivoted to one of said end cranks, a middle crank mounted medially of said shaft, an equalizing bar linked to said middle crank, slotted links each having one end slidably engaging said equalizing bar and the other end pivoted to one of the lower latch bars, an operating crank mounted on said shaft, and an articulated lever pivoted to one of said side boards and pivotally connected to said operating crank.
4. In a tobacco press having side boards, a back board connecting the side boards, and a movable presser board operatively engaging the side boards for movement relative to the back board, means for guiding the said presser board comprising said side boards having transversely extending corresponding slots at one end thereof, and a transverse bar slidably engaging said slots and mounted on said presser board.
5. In a tobacco press having side boards, a back board connecting the side boards, a movable presser board operatively engaging the side boards for movement relative to the back board, and upper and lower latch bars pivoted to the side boards and releasably engaging said presser board, means for simultaneously releasing said latch bars from engagement with said presser board, said means comprising a transverse shaft journaled in said side boards, end cranks mounted at each end of said shaft, flexible elements each having one end pivoted to one of the upper latch bars, and the other end pivoted to one of said end cranks, a middle crank mounted medially of said shaft, an equalizing bar linked to said middle crank, slotted links each having one end slidably engaging said equalizing bar and the other end pivoted to one of the lower latch bars, an operating crank mounted on said shaft, and an articulated lever pivoted to one of said side boards and pivotally connected to said operating crank.
6. A tobacco press having a back board, a presser board movable relatively to the back board, latch bars releasably engaging opposite ends of the presser board, and means for simultaneously releasing said latch bars from engagement with said presser board.
7. A tobacco press having a back board, side boards mounted on the back board, a presser board movable relatively to the back board, said side boards having transversely extending corresponding slots at one end thereof, a transverse bar slidably engaging said slots and mounted on said presser board, upper and lower latch bars releasably engaging opposite ends of the presser board, and means for simultaneously releasing said latch bars from engagement with said presser board.

In testimony whereof I affix my signature.

THOMAS MILLER.
